UNITED STATES PATENT OFFICE

99,378

DESIGN FOR A CAPE OR SIMILAR ARTICLE

Jacob Stein, New York, N. Y.

Application December 27, 1935, Serial No. 60,304

Term of patent 14 years

To all whom it may concern:

Be it known that I, Jacob Stein, a citizen of the United States, residing in the city, county, and State of New York, have invented a new, original, and ornamental Design for a Cape or Similar Article, of which the following is a specification, reference being had to the accompanying drawing forming a part thereof.

In the drawings:—

Fig. 1 is a rear view of a cape showing my design.

Fig. 2 is a side view thereof.

Fig. 3 is a front view of same.

Fig. 4 is a front perspective view of the cape as shown in Fig. 3 with the hood raised to wearing position.

I claim:—

The ornamental design for a cape or similar article substantially as shown and described.

JACOB STEIN.
